United States Patent Office

Des. 188,425
Patented July 19, 1960

188,425

DESCENT RETARDER

Paul M. Lewis, South Gate, Calif.

Filed Oct. 16, 1959, Ser. No. 57,961

Term of patent 3½ years

(Cl. D34—15)

Fig. 1 is a perspective view as seen from one side and one end of a descent retarder showing my new design.

Fig. 2 is a perspective view as seen from the opposite side and the other end.

Fig. 3 is an edge view thereof.

I claim:

The ornamental design for a descent retarder, substantially as shown.
